UNITED STATES PATENT OFFICE.

JOHN SMART MATTHEW, OF SUTTON COLDFIELD, ENGLAND, ASSIGNOR TO THE DUN-
LOP RUBBER COMPANY, LIMITED, OF REGENTS PARK, LONDON, ENGLAND, A
BRITISH COMPANY.

SPOKE-COVERING MEANS.

Application filed February 13, 1922. Serial No. 536,249.

To all whom it may concern:

Be it known that I, JOHN SMART MATTHEW, a British subject, residing at The Manor, Sutton Coldfield, in the county of 5 Warwick, England, have invented certain new and useful Improvements in Spoke-Covering Means, of which the following is a specification.

This invention relates to spoke covering means for vehicle wheels comprising inner and outer discs adapted to be fitted at the sides of the wheel and connecting members disposed between the two discs and attached thereto or to suitable parts on or 10 associated with the discs so that the latter may be retained in position at the sides of the wheel. The present invention relates especially to spoke covering discs for detachable wire spoked wheels for motor vehicles 15 and comprises improvements in the means for securing the discs in position and in the discs themselves.

According to this invention the connecting members are attached to the inner disc 20 at points nearer to the periphery than to the centre of the disc so that they extend across the wheel to anchoring points adjacent to the front or outer end of the hub at a substantial inclination to the axis of the 25 hub. The said anchoring points may be provided on a ring or collar seated at the front or outer end of the hub and the outer disc may be detachably carried by or secured on this ring or collar. The inner disc is preferably shaped or adapted to bear against the 30 inner edge or side of the wheel rim and against the inner end of the hub, whilst the outer disc may bear against the outer edge or side of the wheel rim with its ring or collar bearing against the front or outer end of the hub, so that the two discs can be 35 retained in position without bearing on the spokes. The connecting members may be hooked to eyes, lugs or the like on the inner disc and the said ring or collar and they may be tensioned or adjusted to pull the inner disc and the said ring or collar against their seatings. The wheel for which 40 the discs are especially intended comprises an outer set of inclined spokes and an inner set of substantially vertical spokes. Therefore the outer disc may be coned or dished to a substantial extent to suit the 45 inclination of the outer spokes, whilst the 50

inner disc may be more or less flat. The 55 inner disc, being more or less flat does not possess the rigidity of the outer disc and it may be strengthened, for example, by providing ribs or corrugations thereon which may be adapted to form or receive the 60 eyes, lugs or the like to which the aforesaid connecting members are attached. The discs may be made of metal such as aluminum, tin, steel or of any other suitable material such as fibre or celluloid and they may 65 be grooved or otherwise shaped to fit or seat closely against the wheel rim and the hub. In order that the said invention may be clearly understood and readily carried into effect the same will now be described 70 more fully with reference to the accompanying drawings, in which—

Figure 1 is a diagrammatic transverse sectional view (partly in elevation) showing one embodiment of the invention. 75

Figure 2 is a front view the upper half of which is shown in section with the outer disc removed.

Figure 3 is a sectional detail view of a modified form of the invention. 80

A and B represent respectively the hub shell and rim of an ordinary wire spoked wheel of which the spokes are indicated by the legend S, as shown in Figure 1. C represents the inner spoke covering disc 85 which at its periphery is adapted to fit close against the inner edge or clinch of the rim B and which is provided with a central opening the edge around which is formed to bear against the inner end of the hub shell A as shown in Figure 1. D is the outer spoke covering disc shaped at its periphery to fit against the outer edge or clinch of the rim B whilst it is formed with a central opening to enable it to be placed 90 on a collar D' adapted to be seated on the outer end of the hub shell A. The outer disc D is coned to a substantial degree but the inner disc C is practically flat and consequently does not possess the rigidity of the 95 outer coned disc, the inner disc C may therefore be strengthened by ribs or corrugations provided or formed thereon and in the example shown strengthening ribs in the form of strips C' are attached to the inner disc 100 C and provided with lugs or eyes C² at points near the periphery of the said disc C. E E represent the connecting members 105

or tension rods which are each composed of two short lengths of wire hooked at their outer ends and threaded at their inner ends to screw into oppositely disposed threads 5 in a turnbuckle or socket E'. These rods E are hooked to the lugs C² on the strips C' and to lugs or eyes D² on or in the aforesaid collar D' prior to the outer disc D being placed in position. By rotating the 10 turnbuckles or sockets E', the rods E may be tensioned to pull the inner disc C closely against the rim B and the inner end of the hub shell A and also to retain the ring D' firmly in position on the outer end of the 15 hub shell, without any attachment to or pull on the spokes of the wheel. The outer disc D is then placed on the collar D' so as to bear at its outer periphery against the rim B, and it is retained in position by a nut 20 D³ threaded on to collar D'; preferably a fibre washer D⁴ is interposed between the disc D and the nut D³ as shown in Figure 1. As will be seen from Figure 1 the connecting or tension members or rods E are 25 inclined across the vertical plane of the wheel, so that an efficient seating of the collar D' and the inner disc C in their respective positions can be obtained with less tension on the rods E than would be necessary if the rods were disposed parallel or 30 approximately parallel with the axis of the wheel. Instead of using tension rods E as shown tension springs S as shown in Fig. 3, may be used for connecting the inner disc 35 C and the collar D' together and retaining them in position on the wheel.

What I claim and desire to secure by Letters Patent of the United States is:—

1. Spoke covering means for vehicle 40 wheels, comprising a disc for the inner side of the wheel, connecting members adapted to be attached to the said disc at a point nearer the periphery than the centre of the disc, and anchoring means disposed at the 45 outer end of the hub adjacent to the spokes, the said connecting members being secured to said anchoring means.

2. Spoke covering means for vehicle 50 wheels, comprising an inner disc, a collar at the outer end of the hub, tension members attached to the said inner disc and to said collar for pulling the collar against the outer end of the hub and retaining the disc firmly against the hub and the wheel rim, an outer disc seated around the said collar, and means for retaining the said outer disc against the wheel rim.

3. Spoke covering means for vehicle 60 wheels, comprising an inner disc, a collar seated on the outer end of the hub, adjustable tension members detachably secured to the said inner disc and to the collar and an outer disc detachably secured to the said collar by means independent of the said connecting members.

4. Spoke covering means for vehicle wheels, comprising a substantially flat inner disc, strengthening members thereon, a frusto-conical outer disc, anchoring members secured around a central opening in the outer 70 disc and connecting members attached to the said anchoring members and to the strengthening members on the inner disc.

5. Spoke covering means for vehicle wheels comprising an inner disc formed with a central hole and shaped around this hole to bear against the inner end of the hub, and shaped at its outer periphery to bear against the wheel rim, a collar seated against the outer end of the hub, an outer disc detachably mounted on said collar and shaped at its outer periphery to fit against the wheel rim, and tension members connected to the inner disc and to the aforesaid collar to pull the inner disc and the collar against their 80 respective seatings, the said tension members being fitted prior to the application of the outer disc.

6. Spoke covering means for vehicle wheels comprising an inner disc having anchoring 90 members near its outer periphery, tension members attached to said anchoring members, a collar seated against the outer end of the hub, and formed with anchoring members to which the tension members are connected, a seating on said collar, an outer disc bearing against said seating, and means for retaining the outer disc on the collar.

7. Spoke covering means for vehicle wheels, comprising an inner disc having lugs thereon, a collar having lugs and adapted to be seated on the outer end of the hub, an outer disc, means for retaining the latter disc on the collar and adjustable hook-like connecting members adapted to be connected to the 1 lugs on the inner disc and on the collar.

8. Spoke covering means for vehicle wheels comprising an inner disc provided on its inner surface with members having eyelets therein, a collar formed with eyelets adapted 1 to be seated against the outer end of the hub, tension connecting members hooked to the eyelets on the inner disc and the collar, an outer disc, and means for securing the outer disc on said collar.

9. Spoke covering means for vehicle wheels comprising an inner disc formed with strengthening members having eyelets therein, a collar shaped to abut against the outer end of the hub and formed with eyelets, tension members, each comprising rods having hooks at their outer ends for engaging with the aforesaid eyelets and being oppositely screw threaded at their inner ends so as to be connected by a turnbuckle, an outer disc adapted to be seated on said collar, and means for retaining the outer disc in position on said collar.

10. Spoke covering means for vehicle 1 wheels, comprising a centrally perforated in-

ner disc adapted to bear against the inner end of the hub and against the inner part of the wheel rim, a screw threaded collar adapted to be seated on the outer end of the hub, 5 a centrally perforated outer disc adapted to be seated around said collar and to bear against the outer part of the wheel rim, a securing nut threaded on to the collar for clamping the outer disc thereon, strip-like members attached to the inner disc and provided with lugs, lugs on the said collar, tensioning members each comprising hooked-wires threaded into a turn-buckle, and hooked to the lugs on the said inner disc and on the said collar.

JOHN SMART MATTHEW.
